BRACELET CATCH

Howard J. Leichner, Urbana, Ill., assignor, by direct and mesne assignments, of one-third to Lena Filson and two-thirds to K. L. Filson, both of Champaign, Ill.

Application November 14, 1933, Serial No. 697,975

2 Claims. (Cl. 24—68)

This invention relates to bracelets and more particularly to an improved catch for a bracelet so as to hold the bracelet in adjusted position on the wrist or other member of the wearer.

5 An object of this invention is to provide an improved type of bracelet catch for use with watch bracelets or other link structures whereby the catch can be readily released so as to remove the bracelet or link structure from the desired member and the size of the bracelet or link structure can be varied by the wearer without disconnecting any portion of the links, thereby permitting a finer adjustment of the link structure than is possible where it is necessary to remove a 10 number of links where the bracelet is too large.

15 A further object of this invention is to provide a sliding member in a bracelet catch structure which is held in adjusted position relative to the catch when the catch is in folded or locked position.

20 The above and various other objects and advantages of this invention will in part be described and in part be understood from the following detailed description of the present preferred embodiment, the same being illustrated in the accompanying drawings wherein:—

Figure 1 is a detail side elevation of a device constructed according to the preferred embodiment of this invention.

25 Figure 2 is a front elevation of the device in closed position.

Figure 3 is a bottom plan view of the device in open position.

Figure 4 is an enlarged longitudinal sectional view partly in detail.

Figure 5 is a sectional view taken on the line 5—5 of Figure 4.

Figure 6 is a sectional view taken on the line 6—6 of Figure 4.

40 Figure 7 is a sectional view taken on the line 7—7 of Figure 4.

Figure 8 is a sectional view taken on the line 8—8 of Figure 2.

Figure 9 is a sectional view taken on the line 45 9—9 of Figure 3.

Referring to the drawings wherein like numerals of reference designate corresponding parts throughout the several views, the numeral 10 designates generally a channeled member in the 50 form of an elongated plate 11 provided on opposite sides thereof with a pair of U-shaped channeled members 12.

A swingable link, generally designated as 14, is connected to the channeled member 10 by 55 means of a connecting link 15. This connecting

link 15 is swingably connected at one end to one end of the channeled member 10, the channeled member 10 having hinged barrels 13 on opposite sides of the longitudinal opening 16 between the confronting U-shaped channel members 12. The connecting link 15 is substantially U-shaped in transverse section and is preferably longitudinally curved so as to conform substantially to the curvature of the link structure when it is mounted on the desired part.

In the same manner, the link or bar 14 is preferably U-shaped in transverse section and the hinged barrel 17 at one end of the link or bar 14 is constructed for engagement with the barrel members 13 and with the barrel structure 18 carried by one end of the link 15 when the link 14 is in closed or folded position. This barrel 17 is offset forwardly so that it will frictionally engage against the outer end of the channel member 10, as described. The opposite end of the link 15 is connected, as at 19, to the link 14 at a point intermediate the ends of this link 14. The link 15 is adapted to telescope into the link 14 when in folded position, and the two links 14 and 15 are adapted to engage in the channel or space 16. The parallel legs 20 of the bar or link member 14 are provided with a cut out portion 21 at the end of the link 14 opposite from the barrel 17, the purpose for which will be hereinafter described.

These parallel legs 20 are also provided with detents 22 adjacent the cut out end portion 21, which detents are adapted to engage the confronting edges of the U-shaped members 12 so as to lock one end of the link 14 in folded position. The opposite end of the link 14 is locked in folded position by the tension applied to the hinge barrel 17 engaging over the barrel 13 and the barrel 18.

In order to provide a means whereby the catch including the channeled member 10 and the two links 14 and 15 may be adjusted as to length so that the bracelet or other link structure associated with this catch may be lengthened or shortened, as may be desired, and held in this adjusted position, I have provided a U-shaped slide member generally designated as 23, which is slidable relative to the channeled member 10. This slide and locking member 23 comprises a pair of parallel leg members 24 connected together by means of a slotted connecting bar 25, the slot 26 of which is adapted to receive a link of a conventional bracelet structure. The legs 24 of the slide member 23 are adapted to be loosely received in the U-shaped members 12 on opposite sides of

the channel 16. Each leg 24 has on its inner or free end a lug 27 which is provided with a cam outer surface 28 and a straight inner surface 29.

5 A locking disk or roller 30 is interposed between the cam portion 28 and the bight of the channel member 12, and this disk 30 is adapted, upon movement longitudinally of the slide member 23, to force the lug 27 inwardly against the side of 10 the link 14 when this link 14 is in folded position. Preferably, the cam portion 28 of the lug 27 is inwardly offset from the outer side of the lug 27, so as to provide means for limiting the movement of the locking member 30 and prevent the dis- 15 engagement of this locking member 30 with the cam member 28. The connecting bar 25, when the slide adjusting member 23 is in its innermost position, is adapted to engage in the cut out portion 21 of the link 14, and when the opposite 20 end of the link 14 is raised, the cut out portion 21 will engage against the connecting bar 25 and serve as a fulcrum for releasing the detents 22 from inside the channel members 12.

In the use and operation of the catch herein- 25 before described, the barrel 17 is adapted to be connected to one end of the bracelet or link structure and the slot 26 is adapted to receive the other end of the bracelet or link structure.

30 In order to increase the length of the bracelet or link structure, the catch including the channeled member 10, the slide 23 and the link members 14 and 15, is initially disposed with the link 14 released from the channel member 10, as shown in Figure 1. Preferably, the slide member 23 is initially disposed in an extended position relative 35 to the channeled link member 10 and when the bracelet or link structure has been disposed about the desired part, the link 14 and the link 15 are swung toward the channel member 10 and the detents 22, together with the hinge barrel 17, will 40 hold the catch in folded position. In this position, the parallel legs of the link member 14 confront the straight side 29 of the lug 27 and movement outwardly of the slide member 23 will be 45 resisted by reason of the fact that the rollers or disks 30 will be drawn toward the shallow portion of the cam 28 and thereby force the lugs 27 inwardly against the parallel sides of the link 14. However, the slide member 23 can be moved inwardly of the channel member 10, which movement 50 will shorten or reduce the size of the bracelet or link structure.

It will be apparent, from the foregoing, that an improved catch has been disclosed which can be 55 adjusted by the purchaser of the bracelet or link structure after it has been inserted on the desired member and when it has been so adjusted, it will be locked in adjusted position.

It will also be apparent, from the foregoing, that it will not be necessary to cut any links out of the bracelet as is the practice or to add extra links to the bracelet in order to vary the size of the bracelet to make it fit on the desired member. 5

The end of each U-shaped member 12 opposite from the barrel 13 is provided with a stop lug 31 which engages against the outer end of the lug 27 when the slide 23 is moved outwardly to prevent withdrawal of the slide 23. The locking 10 members 30 may be constructed as rollers, disks or balls, and through the simple construction of the locking means for the slide or connecting link 23, the catch will not readily wear out or get out 15 of order easily, thereby making the catch ex- 20 ceedingly simple, practical and easily adjusted by the seller at the time of the purchase as the bracelet is being mounted on the wrist of the wearer, or it may be adjusted without the aid of tools by the purchaser at will.

It is, of course, understood that various changes and modifications may be made in the details of construction and design of the above specifically described embodiment of this invention without departing from the spirit thereof, such changes 25 and modifications being restricted only by the scope of the following claims.

What is claimed is:—

1. A bracelet catch, comprising a plate member having an edge thereof overturned to form a 30 longitudinally extending channel, means at one end of the plate member for attaching the member to a link structure, a slide member engaging in said channel, means for attaching the slide member to another portion of the bracelet structure, a locking member loosely disposed in said channel, and a cam carried by the slide member and engaging the locking member to lock the slide member against movement in one direction, said locking member being movable lengthwise of 40 the channel upon movement of said slide member.

2. A bracelet catch, comprising an elongated plate member, a pair of longitudinally extending channels one on each side of the member, means for attaching one end of the member to a bracelet 45 structure, a U-shaped slide member having the legs thereof loosely disposed in said channels, said slide member having means in the bight thereof for attachment to another end of the bracelet structure, a cam carried by each free 50 leg of the slide member, and a roller disposed in each channel and engaging the cam for locking the slide member against movement in one direction.

HOWARD J. LEICHNER. 55
